UNITED STATES PATENT OFFICE.

OTIS EAST, OF HASTINGS-UPON-HUDSON, NEW YORK,

CARPENTER'S BEVEL.

Application filed July 26, 1923. Serial No. 653,634.

To all whom it may concern:

Be it known that I, OTIS EAST, a citizen of the United States, and a resident of Hastings-upon-Hudson, county of Westchester, 5 and State of New York, United States of America, have invented certain new and useful Improvements in Carpenters' Bevels, of which the following is a specification.

This invention relates to carpenters' tools 10 and particularly to tools of the type known as bevels or bevel squares.

One object of the invention is to provide a tool of the character described having adjustable blades at both ends of the tool 15 thereby increasing the utility thereof.

Another object of the invention is to provide a tool so constructed that a blade at one end of the handle can be set at one definite angle and the blade at the opposite end can be 20 set at another definite or predetermined angle.

Further objects of the invention will appear from the following description taken in connection with the drawings which form a part of this application and in which, 25 Fig. 1 is a top plan view of a tool constructed in accordance with the invention.

Fig. 2 is a side elevation of the structure shown in Fig. 1.

Fig. 3 is a plan view similar to Fig. 1 but 30 showing certain of the blades adjusted at an angle to the handle.

Fig. 4 is a side elevation of the structure shown in Fig. 3.

Figs. 5, 6, 7 and 8 are sectional elevations taken respectively on lines 5-5, 6-6, 35 7-7 and 8-8 of Fig. 4.

Fig. 9 is a sectional elevation taken substantially on line 9-9 of Fig. 6.

Fig. 10 is a transverse sectional elevation 40 taken substantially on line 10-10 of Fig. 8.

Fig. 11 is a top plan view of the tool shown in Figs. 1-4 and illustrating certain of the blades adjusted at predetermined angles with respect to the handle.

Fig. 12 is a side elevation of the construction shown in Fig. 11.

Fig. 13 is a top plan view of another form of tool constructed in accordance with the invention, and

Fig. 14 is a side elevation of the tool shown in Fig. 12 but showing the blades in folded position.

The invention briefly described consists of a tool comprising a handle having a pair 55 of separate side members and a plurality of blades pivotally and slidably mounted

on pins disposed adjacent the ends of the handle. Certain of the blades are adjustable to predetermined angles with respect to the handle and in the particular embodiments of the invention shown the side members of the handle have means such as shoulders formed thereon for positioning the blades at such predetermined angles, these shoulders forming stops. By providing adjustable blades at both ends of the handle the utility of the tool is increased since a blade at one end may be set at one angle and the blade at the other end may be set at a different angle. Further details of the invention will appear from the following description.

Referring first to the embodiment of the invention shown in Figs. 1-10 inclusive, the handle of the tool comprises side members 20 and 21 which are disposed in spaced relation with respect to each other and are connected by means of pins 22 and 23, each pin having a head 24 at one end thereof and a squared portion 25 adjacent the head and received in a square hole 26 in the side member 21 (Fig. 7). Each pin has threaded on its opposite end a thumb nut 26^a for clamping the blades in adjusted position between the side members of the handle.

Each pin has pivotally and slidably mounted thereon a plurality of blades and in the embodiment shown in Figs. 1-10, blades A and B are mounted on pin 23 and blades C and D are mounted on pin 22. Each of these blades has a longitudinal slot 30 therein, the pins being disposed in the slots of the blades. The blades are also beveled at their free ends as shown at 31. The side member 20 of the handle has a shoulder 32 (Fig. 5) against which the beveled end 31 of the blade D seats when this blade is in folded position. The side member 21 of the handle has a shoulder 33 against which the end 31 of the blade A seats when this blade is in folded position.

Means is provided on the side member 20 for positioning the blade B at right angles to the handle and this means consists of a beveled shoulder 35 adapted to engage a beveled edge portion 36 of the blade B when this blade is swung to a position at right angles to the handle.

Means is also provided on the side member 21 for positioning the blade C at an angle of 45 degrees with respect to the handle. This means consists of a beveled

shoulder 37 engageable by a beveled edge 38 of the blade C when this blade is swung to an angle of 45 degrees with respect to the handle. The beveled ends 31 of the 5 blades B and C engage respectively the pins 22 and 23 when these blades are in folded position.

With the form of the invention shown in Figs. 1-10 inclusive and just described, the 10 blades A and B may be swung to any desired angle with respect to the handle or these blades may be retained in folded position and the blades B and C may be swung respectively to angles of 90 degrees and 45 degrees with respect to the handle. The blades 15 may be clamped in any desired degree of adjustment by means of the thumb nuts 26.

In Figs. 11 and 12 the blade B is swung to a position at 90 degrees with reference to 20 the handle and the beveled edge 36 of this blade engages the beveled shoulder 35 formed on the side member 20.

Also in these figures the blade C is swung to a position at 90 degrees to the handle and 25 the beveled edge 38 of this blade engages the beveled shoulder 37 formed on the side member 21 of the handle. The blades A and D are in folded position and the thumb nuts 26 are turned until the blades B and C are 30 firmly clamped between the side members 20 and 21 and are thereby retained in adjusted position.

A simpler form of the invention is illustrated in Figs. 13 and 14 inclusive, and in 35 these figures one blade is mounted on each end of the device. The handle in this embodiment comprises side members 40 and 41 connected by pins 42 and 43 having heads 44 and squared portions 45 received by 40 square openings in the side member 41. Thumb nuts 46 are threaded on the pins 42 and 43. A blade E is pivotally and slidably mounted on the pin 42 and the blade F is similarly mounted on the pin 43. These 45 blades are beveled as shown at 47 at their free ends. The beveled end of the blade F seats against a shoulder 48 formed on the side member 40 and the beveled end of the blade E seats against a shoulder 49 formed 50 on the member 41. The blades E and F may be swung to any desired angle with respect to the handle and may be clamped in adjusted position by means of the thumb nuts 46.

55 Although certain specific embodiments of the invention have been particularly illustrated and described, it will be understood that the invention is capable of modification and that further changes in the construction 60 and in the arrangement of the various co-operating parts may be made without departing from the spirit or scope of the invention as expressed in the following claims.

What I claim is:

65 1. A tool comprising a pair of side mem-

bers disposed in spaced relation, pins connecting said members and located adjacent the ends thereof, an adjustable blade mounted on each pin and foldable between the side members, and raised means of the thickness 70 of the adjacent blade on said side members forming stops for limiting the pivotal movement of another of said blades and positioning said other blades at predetermined angles with respect to the side members. 75

2. A tool comprising a pair of side members disposed in spaced relation, pins connecting said members and located adjacent the ends thereof, a slotted, adjustable blade mounted on each pin and foldable between 80 the side members, and shoulders on said side members forming stops for limiting the pivotal movement of another of said blades and positioning said other blades at predetermined angles with respect to the side members. 85

3. A tool comprising a pair of side members disposed in spaced relation, pins connecting said members and located adjacent 90 the ends thereof, an adjustable blade mounted on each pin a shoulder on each side member raised to the thickness of the adjacent blade and means on said pins for clamping the blades in adjusted position. 95

4. A tool comprising a pair of side members disposed in spaced relation, pins connecting said members and located adjacent the ends thereof and adjustable blades mounted on said pins and foldable between 100 the side members and beveled shoulders on said side members raised to the thickness of the adjacent blades forming stops for limiting the pivotal movement of others of said blades and positioning the blades at predetermined angles with respect to the side members, such of said blades as are thus positioned by the beveled shoulders having edges beveled to cooperate with the bevel of the shoulders. 105

5. A tool comprising a pair of side members disposed in spaced relation, pins connecting said members and located adjacent the ends thereof and adjustable blades mounted on said pins and foldable between 110 the side members and beveled shoulders on said side members raised to the thickness of the adjacent blades forming stops for limiting the pivotal movement of others of said blades and positioning the blades at predetermined angles with respect to the side members, such of said blades as are thus positioned by the beveled shoulders having edges beveled to cooperate with the bevel of the shoulders, and other adjustable blades 115 also mounted on said pins, the blades which are arranged to be positioned by said shoulders being provided with slots. 120

In witness whereof, I have hereunto set my hand this 14th day of July, 1923.

OTIS EAST.
